UNITED STATES PATENT OFFICE.

ISHAM MELTON, OF MOUNT HOLLY, ARKANSAS.

DESK.

SPECIFICATION forming part of Letters Patent No. 380,045, dated March 27, 1888.

Application filed November 8, 1887. Serial No. 254,627. (No model.)

To all whom it may concern:

Be it known that I, ISHAM MELTON, a citizen of the United States, residing at Mount Holly, in the county of Union and State of Arkansas, have invented certain new and useful 5 Improvements in Desks; and I do declare the following to be a full, clear, and exact description of the invention, such as will enable others skilled in the art to which it appertains 10 to make and use the same, reference being had to the accompanying drawings, and to the letters and figures of reference marked thereon, which form a part of this specification.

My invention has relation to desks; and it 15 consists in the novel construction and arrangement of its parts.

Figure 1 is a perspective view of my invention open. Fig. 2 is a perspective view of the same closed.

It is described as follows: The body of the desk consists of the two upright end pieces, A, the upper cross-piece, a, and the lower cross-piece, a'. The upper cross-piece, a, is secured between the end pieces about a foot from their 25 top, so as to form a shelf for books, ledgers, &c., the end pieces extending far enough up to form end guards, e'. The cross-piece a' is secured between the said end pieces, A, about equidistant from either end, and has secured 30 to its front and rear edges and to the said end pieces side piece, a'', forming a trough, a'', for the purpose of holding inks, pens, pencils, rubber, &c. Between the said end pieces, the upper cross-piece, a, and the trough a'' are constructed book-shelves and pigeon-holes B. To either end and on both sides of the main body of the desk are secured legs b by means of 35 hinges b', which are secured at their upper ends to the upper cross-piece, a. The said 40 legs are so constructed that they may be opened out to answer as braces, and thus hold the said desk in an upright position, and they are kept from opening too wide apart by means of stays c, made of flexible material, one of 45 which is fastened to each end piece, A, at its middle, while its ends are fastened to the said legs b. These stays, however, may be made of metal having an elbow-joint, or of any other material and in any known form, their office 50 simply being to keep the said legs from opening too wide apart. To the inner face of each

of the said legs are secured sockets d. Swung in these sockets by means of rods d' are leaves E, which when open form the leaves of the desk, and which when shut answer for doors 55 to protect the books, papers, inks, &c., in said desk. These leaves E have each a lower end, e, which extends down below the hinging-point, below the rod d', secured to said leaves by sockets d'', and when the said leaves are let 60 down the said lower ends, e, catch under the trough a'' and hold the said leaves in proper position for use. It is immaterial which leaf is let down first, because their lower ends do not meet under the trough, and will therefore 65 not impinge each other. To the lower ends of the leaves E are secured, by staples or otherwise, a chain or chains, g, opposite ends being secured to opposite leaves, said chain being just as long as the end pieces are wide, so that 70 when the said leaves are shut up the chain or chains are taut and hold the legs firmly against the said trough, bringing their outer faces flush with the edges of said end pieces and the outer surface of the said leaves, giving a neat 75 and compact finish. Thus the said legs and the said leaves combine to form a door or doors to protect the material in the desk.

When the desk is not in use, the leaves may be shut up, which operation closes up the 80 legs. If it is not desired to close the legs, one end of the chain may be unhooked from the leaf.

The leaves E may be made of or covered with such material that they may be used as 85 blackboards.

Having described my invention, what I claim as new, and desire to secure by Letters Patent, is—

1. The combination of the end pieces, A, 90 having extensions e', upper cross-piece, a, and trough a'', secured between said end pieces, shelving B, set above said trough between said end pieces, legs b, hinged at their upper ends to said cross-piece by the hinges b', stays c, 95 secured to said end pieces and said legs, leaves E, pivoted in the sockets d on said legs by means of the rods d', secured to said leaves, and the chains g, secured to the lower ends of said leaves, substantially as shown and described, and for the purposes set forth. 100

2. The combination of the end pieces, A,

upper cross-piece, *a*, and trough *a'*, secured between said end pieces, shelving *B*, set above said trough and between said end pieces, legs *b*, hinged at their upper ends to the said cross-piece *a*, stays *c*, secured to the said end pieces and said legs, leaves *E*, pivoted in the sockets *d* by means of the rods *d'*, secured to said leaves, said leaves *E* having extensions *e*, adapted to catch under the trough *a'* to hold

10 said leaves in proper position for use, all substantially as shown and described, and for the purposes set forth.

In testimony whereof I affix my signature in presence of two witnesses.

ISHAM MELTON.
